UNITED STATES PATENT OFFICE.

LEON P. JEANNE, OF NEW YORK, N. Y., AND PAUL JEANNE, OF GREENVILLE, NEW JERSEY.

BRACELET.

SPECIFICATION forming part of Letters Patent No. 241,020, dated May 3, 1881.

Application filed March 5, 1881. (No model.)

To all whom it may concern:

Be it known that we, LEON P. JEANNE, of the city, county, and State of New York, and PAUL JEANNE, of Greenville, in the county of 5 Hudson and State of New Jersey, have invented a new and Improved Bracelet, of which the following is a full, clear, and exact description.

The object of this invention is to provide a bracelet combining strength and flexibility in 10 a superior degree, capable of easy adjustment to the arm, and incapable of becoming unclasped.

The invention consists of a bracelet made of a narrow thin strip of metal wound closely and 15 spirally about a chain; and it further consists of a novel device for adjusting and fastening the bracelet, all of which will be hereinafter described.

Figure 1 is a plan of the bracelet with parts 20 broken away to exhibit other parts. Fig. 2 is a side elevation of the same.

Similar letters of reference indicate corresponding parts.

In the drawings, A represents a chain of 25 ordinary construction, preferably made with a round, or nearly round, cross-section. Around this chain A is wound spirally a narrow thin strip or covering, B, of metal, so that the edges of said strip B are in contact with each other. 30 In this manner the body of the bracelet is formed of great strength and pliability.

In order to hold the parts A B together, a metallic cap or tip, C, either plain or ornamented, is fastened in a suitable manner on each 35 end of the said bracelet, as shown.

D D' represent two sleeves, linked together by a diagonal link or brace, D². Through the sleeve D, which has an unbroken surface, one end of the bracelet is passed and fastened, and 40 the opposite end of the bracelet is passed in a contrary direction through the other sleeve, D', which has a spiral slot, a, extending longitudinally through it, so that this end of the bracelet can be drawn in and out of said sleeve D', and the bracelet be thereby contracted or made 45

larger, as may be desired. The tip C prevents it from being drawn out altogether.

In order to hold the bracelet in the position to which it may have been contracted or enlarged, several studs, b, are fixed in that part 50 of it which passes through the sleeve D', so that by taking hold of the extremity of this end of the bracelet and turning it to bring one of the studs b opposite the slot a, and then pulling said end, the stud b will be drawn through 55 said slot a, thereby contracting the bracelet; then, by turning the end of the bracelet in the opposite direction, the said stud b will take against the outer end of the sleeve D', and thereby lock or fasten the bracelet, as shown. 60 By reversing this action the bracelet may be enlarged. In both instances the tension of the spiral B tends to hold the bracelet locked.

Having thus described our invention, what we claim as new, and desire to secure by Letters Patent, is—

1. As an improved article of manufacture, a bracelet constructed, substantially as herein shown and described, of chain A and spiral covering B, as set forth.

2. In a bracelet, the combination, with the chain A and spirally-wound covering B, of the tips C, substantially as herein shown and described, whereby said chain and covering are secured together, as set forth.

3. In a bracelet, the combination, with the chain A and spirally-wound covering B, provided with studs b, of the linked sleeves D D', provided with spiral slot a, substantially as herein shown and described, whereby said 80 bracelet is adjusted and fastened, as set forth.

4. As a means for adjusting and locking a bracelet, a spirally-slotted sleeve, substantially as herein shown and described.

LEON P. JEANNE.
PAUL JEANNE.
